UNITED STATES PATENT OFFICE.

JOHN J. SULLIVAN, OF IPSWICH, MASSACHUSETTS, ASSIGNOR TO HAMEL SHOE MACHINERY COMPANY, OF LYNN, MASSACHUSETTS, A CORPORATION OF MASSACHUSETTS.

HEEL-BREASTING MACHINE.

1,129,137.

Specification of Letters Patent. Patented Feb. 23, 1915.

Application filed October 2, 1914. Serial No. 864,607.

To all whom it may concern:

Be it known that I, JOHN J. SULLIVAN, a citizen of the United States, residing at Ipswich, county of Essex, State of Massachusetts, have invented a certain new and useful Improvement in Heel-Breasting Machines, of which the following is a specification, reference being had therein to the accompanying drawings.

10 The hereinafter described invention is an improvement on the heel breeding machine shown and described in my application filed May 27, 1914, Serial No. 841,364, and relates particularly to the type of machine shown 15 in Figure 5 of said application but not specifically claimed therein, in which a single trimming knife is employed, the heel being supported against a suitably shaped cutting block, the face of which is movable to present different portions thereof to the edge of the knife.

20 My present invention has for its object to combine with a heel breeding machine of this type means for simultaneously breeding the top lift of the heel, the upper edge of which cannot be satisfactorily breasted by a knife or knives moving inwardly from the sides toward the center of the heel; also to breast the top lift and intermediate lifts 25 concavely to give to the heel a more attractive appearance. I accomplish these objects by providing a vertically moving knife which automatically breeds the inner side of the top lift after the horizontally moving knife has formed the front of the heel. 30 As the pressure produced by the vertically moving breeding knife is exerted directly against the operator who holds the shoe on its jack in operative position, I have provided means for positively supporting the jack while the cutting is taking place. The machine also contains certain other important improvements which will be hereinafter 35 fully described.

40 In the drawings, Fig. 1 is a front elevation of a machine embodying my invention. Fig. 2 is a section on line 2—2 of Fig. 1, looking in the direction of the arrows. Fig. 3 is a top plan view of the portion of 45 the machine surrounding the vertical knife. Fig. 4 is a section on line 4—4 of Fig. 1 looking in the direction of the arrows. Fig. 5 is a detail of the cam and connected parts by which the vertical knife is operated. 50 Fig. 6 is a top plan view of the jack sup-

port. Fig. 7 is a bottom plan view of the heel rest. Fig. 8 is a view in perspective of the breast of a heel showing the cuts produced by the two breeding knives.

Referring to the drawings, and particularly to Fig. 8 at A is shown a heel which has been breasted by the machine embodying my present invention. The horizontal cut 60 designated by *a* is made by a concave horizontal breeding knife, the shoe being supported against a cutting block which will be described later. The vertical cut is designated *b* and is made by a vertical knife 65 called for convenience the top breeding knife. It will be seen that the vertical cut 70 passes down through the top lift and several adjacent lifts and merges into the horizontal cut thereby forming a heel of exceptional appearance.

Referring now to Fig. 1, at 10 is shown 75 the table of the machine. On this table are located three standards 11, 12, and 13, which support the various working instrumentalities of the machine. The cutting block is shown at 14 and is circular in form having 80 an edge contour corresponding with the exterior of the heel to be trimmed so that an adequate support will be furnished the heel while it is being trimmed. It is mounted on a shaft 15 so that it is revoluble and can 85 be moved from time to time by the operator to prevent it wearing too much in one place. The shaft 15 is mounted in a fork 16 being adjustable vertically therein by means of the set screws 17, 17. The fork 16 is mounted 90 on one end of the slide 18 in the standard 11 and is adjustable longitudinally by means of the adjusting screw 19 and set screw 20. These parts hold the block firmly but permit such adjustments as are necessary from 95 time to time. At 21, is shown the horizontal knife which for convenience I have called the breast knife. This is mounted on one end of the slide 22 the ends of which pass through suitable guideways in the standards 100 12 and 13. The breast knife bar 22 is reciprocated horizontally by the crank arm 23 pivoted at one end to the collar 24 and at the other end to the crank pin 25 on the gear 26. The gear 26 meshes with the small gear 105 27 on the main shaft 28. The gears 26 and 27 have a two-to-one ratio so that the breast knife will make a complete reciprocation for each two revolutions of the main shaft 28.

The machine is provided with a clutch and 110

stop mechanism of the general type shown in my prior application. It consists in a roll and cam clutch 29 and a cam 30 having a notch 31 in its face.

5 At 32 (see also Fig. 4) is shown the starting lever. This lever hangs from the under side of the table and is fast to a rod 33 on the other end of which is a forked arm 34 which surrounds the vertical pin 35 engaging a suitable notch 36 therein. The end of the pin 35 is in the path of rotation of the notched cam 30. A spring 37 tends to hold the forked arm 34 and pin 35 in their uppermost position so that the end of the pin 35 is in the path of the cam except when pulled down by the movement of the starting lever to start the machine. It will therefore be seen that when the starting lever 32 is moved the cam 30 is released, the inner clutch member 38 is released and the machine starts and continues to revolve until the cam 30 engages the end of the pin 35.

At 38, is shown a cam mounted on the shaft 39 on which the beveled gear 26 rotates. This cam is above the end of a pin 40, the lower end of which rests against the hand lever 32, and is so placed on the shaft 39 which, as previously stated, makes one revolution for each two revolutions of the main shaft 28 on which is located the stop cam 30, that the lever 32 after being pulled down to start the machine is held down by the pin 35 and out of engagement with the cam 30 for a little more than a revolution of the main shaft. The pin 35 is then released by the cam 38 so that thereafter the end of the pin 35 is held against the edge of the cam 30 and stops the machine, when the notch in the cam comes around again. It will be seen that this mechanism provides simple and effective means for causing the breast knife to come to rest after each complete reciprocation.

At 42, is shown the top breasting knife by which the front edge of the top lift and of some of the intermediate lifts is formed. As will be seen in Fig. 2, the breast knife 21 is made slightly narrower than the height of the breast of the heel so that it will not breast the front of the top lift, this edge being left to be breasted by the top breasting knife. The top breasting knife is concave as shown and is secured to a slide 70 which moves vertically in a guideway, see Fig. 3, which is formed in a block 43 mounted on one end of the adjustable stud or shaft 44 on the cross frame 45 which extends across between the two standards 11 and 12. The top breasting knife 42 is reciprocated vertically in its slide by an arm 46 pivoted at 47 to the cross frame. The top breasting knife 42, slide 70 and arm are pivotally connected by a bolt 48.

The top breasting knife is maintained normally in its highest vertical position by

means of a spring 49 the lower end of which is secured to the standard 12. The rear end of the top breasting knife arm 46 carries a downwardly extending stud 50 on the lower end of which is located a cam piece 51. This cam piece 51 is in the path of a similar cam piece 52 formed conveniently on the upper end of the crank pin 25. It will therefore be seen that once in each revolution of the beveled gear 26 the cam pieces 51 and 52 will contact and the top breasting knife will be reciprocated being returned to its normal position by the spring 49 when the said two cam surfaces move out of contact with each other. This movement of the top breasting knife is timed to take place after the breast knife 21 has moved out of contact with the heel of the shoe. There is therefore no danger of collision between the two knives.

The last 53 on which the shoe is supported is placed on the upper end of a pin 54 slidable vertically in the bracket 55. A pin 51 moving in a slot 72 in the bracket 55 limits the downward movement of the pin 54. The bracket 55 is pivoted by a pin 73 to a slide 74 and is secured in any desired position of adjustment by the cap screw 75, there being a slot 76 to permit the angular adjustment of the bracket. The slide 74 is movable horizontally in suitable guideways in the table of the machine. The jack pin 54 rests on the head of a pin 60 slidable vertically in the table. The lower end of this pin 60 rests on one end of the lever 56 pivoted to two lugs 57 depending from the under side of the machine. The lever is operated by a treadle 58 and treadle connection 59. It will be seen that the flat head of the pin 60 permits an adjustment horizontally of the jack pin 54 by the adjustment means previously described without interfering with the pin 60 and lever 56 which form the jack lifting mechanism.

At 61 is shown a wedge which is slidable on the table of the machine, being moved by a lever 64 pivotally connected therewith at 63. The wedge 61 is provided with a projection 80 which enters a cutaway space 81 on the under side of the pin 60. When the last has been raised, the operator pushes the wedge under the head of the pin 60 to hold the last with the shoe thereon firmly against the under side of the heel rest 67, thereby relieving himself of the strain resulting from the downward pressure of the top breasting knife. The heel rest 67, see particularly Fig. 7, is provided with an edge 84 against which the back surface of the heel rests and is secured to the under side of a barrel 79 which is vertically adjustable by means of the thumb screw 66. The heel rest is provided with a pin 82 which slides into a suitable hole in the lower end of the barrel and is held in proper position by the set screw 83. It will be seen that the heel

rest may be moved slightly forward or back and then firmly secured in position thereby forming satisfactory means for accurately positioning the heel with relation to the 5
breasting knives.

What I claim is:

1. A heel breasting machine comprising a rotary cutting block conforming in contour to the side of the heel, and a knife of suitable 10
contour movable across the breast of the heel into contact with the cutting block.

2. A heel breasting machine comprising a knife of suitable contour movable from side 15
to side of the breast of the heel, and a knife movable from the top lift toward the heel seat.

3. In a heel breasting machine, the combination of a knife of suitable contour movable from side to side of the breast of the heel, a top 20
breasting knife movable from the top lift toward the heel seat, and means, for reciprocating said knives successively.

4. In a heel breasting machine, the combination of a cutting block conforming in contour to the side of the heel, a knife of suitable 25
contour movable from side to side of the breast of the heel, a top breasting knife movable from the top lift toward the heel seat and means for reciprocating said 30
knives successively.

5. In a heel breasting machine, the combination of a breasting knife having a curved cutting edge movable from side to side of the breast of the heel, a top breasting 35
knife having a curved cutting edge movable from the top lift toward the heel seat, and means for reciprocating said knives, said knives being so located that the cut made by 40
the top breasting knife will merge into that made by the other knife and will form a compound curve.

6. In a heel breasting machine, the combination of a rigid heel support, a jack, means 45
for moving the jack to bring the heel of the shoe into contact with the heel support, a

cutting block conforming in contour to the side of the heel, and a breasting knife of suitable contour moving across the breast of the heel into contact with the cutting block.

60

7. In a heel breasting machine, the combination of a cutting block conforming in contour to the side of the heel, a rigid heel support, a jack, jack lifting means for moving the jack to bring the heel of the shoe into 55
contact with said heel support, positive means engaging said jack lifting means to maintain the jack rigidly in lifted position, and a breasting knife of suitable contour movable across the breast of the heel into 60
contact with the cutting block.

8. In a heel breasting machine, the combination of a breasting knife of suitable contour movable across the breast of the heel, a top 65
breasting knife movable from the top lift toward the heel seat, a shaft, a crank thereon, connections to said first mentioned knife, an arm to move the top breasting knife, and connections between said arm and said shaft to reciprocate the said arm 70
once for each reciprocation of the breasting knife.

9. In a heel breasting machine, the combination of a breasting knife of suitable contour movable across the breast of the heel, a top 75
breasting knife movable from the top lift toward the heel seat, a shaft, a crank thereon, connections to said breasting knife, a cam rotated with said shaft, and an arm to move said top breasting knife by contact 80
with said cam, said cam being so placed with relation to said crank that the movements of said two knives will be successive.

In testimony whereof I affix my signature, in presence of two witnesses.

JOHN J. SULLIVAN.
